CLAIM

The ornamental design for a display screen with graphical user interface as shown and described.

DESCRIPTION

FIG. 1 is a front view of a first embodiment of a display screen with graphical user interface;

FIG. 2 is a first front detail view of a portion of the first embodiment of the display screen with graphical user interface;

FIG. 3 is a second front detail view of a portion of the first embodiment of the display screen with graphical user interface;

FIG. 4 is a front view of a second embodiment of a display screen with graphical user interface;

FIG. 5 is a first front detail view of a portion of the second embodiment of the display screen with graphical user interface;

FIG. 6 is a second front detail view of a portion of the second embodiment of the display screen with graphical user interface;

FIG. 7 is a front view of a third embodiment of a display screen with graphical user interface;

FIG. 8 is a first front detail view of a portion of the third embodiment of the display screen with graphical user interface; and,

FIG. 9 is a second front detail view of a portion of the third embodiment of the display screen with graphical user interface.

The dot-dash broken lines indicate where the enlargements have been taken and form no part of the claimed design. The remaining broken lines showing a display screen and elements of the graphical user interface illustrate portions of the article and form no part of the claimed design.
